UNITED STATES PATENT OFFICE.

CHARLES ALAN SAWYER, OF WORCESTER, MASSACHUSETTS, ASSIGNOR TO GRATON AND KNIGHT MANUFACTURING COMPANY, OF WORCESTER, MASSACHUSETTS, A CORPORATION OF MASSACHUSETTS.

ROUND BELTING.

1,207,083.

Specification of Letters Patent.

Patented Dec. 5, 1916.

Application filed August 16, 1915. Serial No. 45,692.

To all whom it may concern:

Be it known that I, CHARLES ALAN SAWYER, a citizen of the United States, residing at Worcester, in the county of Worcester 5 and Commonwealth of Massachusetts, have invented a new and useful Improvement in Round Belting, of which the following, together with the accompanying drawings, is a specification.

10 The present invention relates to round belting, of the type formed by imparting a spiral twist to a strip of leather or other suitable material.

15 The invention resides particularly in the construction by which an improved belting of the above type is obtained, as fully set forth in the following description, and illustrated in the accompanying drawings, in which—

20 Figure 1 is a plan view of a strip of leather or other material suitable for belting of the type illustrated by my invention. Fig. 2 is a view of the same strip, which has had imparted thereto an initial fold. Fig. 3 is

25 a view of the same folded strip in the process of being twisted to form the belting of my invention. Fig. 4 is a perspective view of the end of strip of belting shown in Fig. 1. Fig. 5 is a perspective view of the end 30 of the folded strip shown in Fig. 2. Fig. 6 is a perspective view, on the section indicated by the line 6—6, Fig. 3, showing the folded strip partially twisted. Fig. 7 is a perspective view, on the section indicated by the line 7—7, Fig. 3, showing the folded strip completely twisted.

Similar reference characters refer to similar parts in the different figures.

40 In the manufacture of my improved belting, a strip 1 of leather, or other suitable material, of the proper width, preferably finished or dressed on at least one surface, is folded lengthwise upon itself to form a more or less rounded doubled edge 2, the finished surface being outside, as shown in Figs. 2 and 5. The edges of the two sides 45 3 and 4 of said fold are thereby brought adjacent one another; the edge 5 of the under side 3 is preferably rounded or beveled off, as shown in Fig. 5, by removing a portion of the smooth or finished outside surface of

the side 3, for a purpose which will hereinafter appear. Likewise, the edge 6 of the other side 4 of the fold may be less acutely beveled than the edge 5, for a purpose which 55 will hereinafter appear.

When the folded strip above described is twisted in a clockwise direction, as shown in Figs. 3 and 6, the side 4 of the fold is disposed inwardly, forming thereby a central 60 core for the belting. The side 3 of the fold constitutes the outer surface of the belting substantially surrounding the core which is formed by the other side 4 of the fold, as shown in Figs. 6 and 7. The free edge 65 6 of the side 4, being coextensive with the free edge 5 of the side 3, becomes interposed, when the folded strip is twisted, between said free edge 5 and the doubled edge 2 of the fold. In consequence of this, the 70 tighter the twist imparted to the belting, the more firmly with the edge 6 be squeezed or pinched between the edge 5 and the doubled edge 2, thereby receiving the full effect of the twist, and acting as an abutment 75 to keep the edges 2 and 5 out of contact. The completed belting, therefore, will always present, on its outer surface, the full width of the free edge 6, spirally disposed, and separating the edge 5 from the edge 80 2, and preventing any deformation of these edges under an excessively tight twist imparted to the belting.

The rounding or beveling of the free edge 85 5 provides a surface which merges substantially into the cylindrical contour of the outer surface of the belting, when completely twisted, as clearly shown in Fig. 7; the same is true of the less acute bevel given the free edge 6 of the strip. 90

I claim,

1. As a new article of manufacture, a round twisted belt formed from a strip folded longitudinally upon itself along its center to bring its opposite free edges together and subsequently folded and twisted to bring one of its free edges between the doubled edge and the other free edge. 95

2. As an article of manufacture, a round twisted belt formed from a strip folded longitudinally substantially at its center and twisted to bring its free edges toward its 10

doubled edge, with each of its free edges exposed.

3. As an article of manufacture, a round twisted belt formed from a single strip having one of its edges beveled and folded upon itself longitudinally along its center to bring its free edges together, and subsequently folded and twisted to bring its free edges

toward its doubled edge, with said beveled edge outermost

Dated this 13th day of August, 1915. 10

CHARLES ALAN SAWYER.
